UNITED STATES PATENT OFFICE.

CARROLL M. SHERIDAN, OF NEW YORK, N. Y.

PORTABLE HEATER FOR HAIR CURLERS.

Application filed October 6, 1921. Serial No. 505,745.

To all whom it may concern:

Be it known that I, CARROLL M. SHERIDAN, a citizen of the United States, and a resident of the city, county, and State of 5 New York, have invented a certain new and useful Improvement in Portable Heaters for Hair Curlers, of which the following is a specification.

This invention relates to a portable and 10 compact casing adapted to contain a ladies' hair curling device and means for heating the same.

The object of this invention is to provide a small and compact container adapted to 15 be carried in a hand-bag or the like, occupying but little space, and containing a hair curler and means for heating the same rapidly whereby the hair curler can be heated and made ready for use without in- 20convenience or delay.

With these objects and other objects which may hereinafter appear, in view, I have devised the particular arrangement of 25 parts hereinafter set forth and more particularly pointed out in the claims appended hereto.

Reference is to be had to the accompanying drawing forming a part hereof in which—

30 Figure 1 is a plan view of the container for my heating device;

Figure 2 is a plan view of the same with the cover removed disclosing the interior of the container and its contents;

35 Figure 3 is a vertical sectional view of the container and its contents;

Figure 4 is a side elevation of the igniting member of the heater;

Figure 5 is a sectional view on the line 40 5—5 of Figure 4 looking in the direction of the arrows;

Figure 6 is a plan view of a modified form of container and contents thereof;

Figure 7 is a side elevation of the structure shown in Figure 6, parts of the same being broken away, and in section, to disclose construction, and

45 Figure 8 is a perspective view of the upper end of the container shown in Figures 50 6 and 7.

Throughout the various views of the drawings, similar reference characters designate similar parts.

Referring first to the construction dis- 55 closed in Figures 1 to 5 inclusive. Here is shown a container 1 which is preferably

made as small and compact as possible so that the same can be readily carried in a hand-bag or the like.

The container 1 is provided with a suitable cover 2 which may be hinged to the container 1 or simply slid thereon, and frictionally held in place as may be desired. It will be understood that the shape of the container may be varied in many ways to suit 60 its contents and it may be suitably ornamented to provide an article of desirable and pleasing appearance.

The container is provided with a pocket forming a well 3 adapted to hold a hair 70 curler 4 of the conventional form. The hair curler disclosed herein is of a well known type provided with a pair of distensible jaws 5 and 6 adapted to be separated by pressing together the arms 7 and 8. In 75 order to enable the hair curler to be compactly stored within the receptacle I find it desirable to provide the arm 7 with a joint 9 whereby the portion 10 of the arm 7 may be folded down at an angle to the hair 80 curler as disclosed in Figures 2 and 3.

At 11 is shown a reservoir adapted to contain alcohol or some other inflammable liquid 12. It will be understood that if desired, the reservoir 11, instead of being 85 integrally formed as part of the container, may be a separate removable tube or the like fitted in place within the receptacle 1.

In the embodiment of my invention disclosed in Figure 3 a tubular wick 12 is 90 contained within the reservoir 11 and is adapted to be ignited as will be hereinafter set forth. The reservoir 11 is kept normally closed by means of a threaded cap 14 provided with a serrated periphery as at 15 95 to permit ready removal of the same. At 16 is provided a well intended to receive an igniting device 17. The igniting device comprises a stem 18, provided at separated points with a plurality of laterally projecting arms 19 and 20 connected by absorbent platinum wires 21.

For convenience in permitting the insertion and removal of the igniting device in the reservoir 11, it is provided at its upper 105 end with a ring 22 adapted to be manually grasped. To hold the igniting device securely, I provide a pivoted clip 23 which engages the upper end of the igniting device and holds the same securely within its 110 well 16.

It will be seen that to use the device the

igniting member 17 is removed from its well 16 and thrust within the reservoir 11. This causes the saturated wick 13 to be ignited and the same throws a flame of intense heat so that the hair curler may be held over the flame and quickly heated and ready for use.

It will be obvious that the position of the wells 3 and 16 may be changed to provide a more compact form of receptacle; that the reservoir may be separated and removed from the container and the general form or outline of the container may be changed in many ways without departing from the spirit of my invention.

In Figures 6, 7 and 8 a modified form of construction is disclosed wherein I provide a container 25 having a well 26 for containing the hair curler 14, said curler being preferably in all respects similar to the hair curler disclosed in Figure 3. The container 25 is provided with a fuel reservoir 27 containing the inflammable liquid 12 in which is held a wick 28, said wick protruding above the upper end of the reservoir 27, the protruding portion of the wick being adapted to be ignited as will be hereinafter set forth. The upper portion of the wick is adapted to be covered by a closure cap 29 threaded down upon the reservoir 27.

At 30 is shown an igniting member consisting of a piece of hardened steel or the like, which is adapted to be scraped or rubbed on a piece of spark-producing substance 32 secured on the upper end of the casing 25 adjacent to the fuel reservoir 27. To use this device the igniting member 30 is

simply removed from its position and struck against the spark producing member 32 which throws a spark against the protruding wick 28 causing the same to be ignited. The hair curler 4 is then held over the flame until heated and ready for use.

It will be seen from the foregoing that various modifications of my invention may be made without departing from the spirit of my invention, the aim of which is to produce a complete, compact casing adapted to contain a hair curler and means for heating the same.

Having described my invention what I claim is:

1. An article of the class described comprising a casing having a well adapted to receive an inflammable material, another well adapted to receive an igniting device for said inflammable material, a cover for said casing, and a third well being adapted to receive a hair curler, the handle of which is adapted to lie parallel to the cover when said cover is closed on the casing.

2. An article of the class described comprising a casing having a plurality of pockets spaced side by side, one of said pockets adapted to receive an inflammable liquid, another pocket adapted to receive means for igniting said liquid, and another pocket adapted to receive a hair curler, a cover for one of said pockets and a cover for the casing.

Signed at the city, county, and State of New York this 4th day of October, 1921.

CARROLL M. SHERIDAN.
